DESIGN FOR A BOTTLE

Reuben Robert Smith, Philadelphia, Pa., assignor to Continental Distilling Corporation, Philadelphia, Pa., a corporation of Delaware

Application May 20, 1937, Serial No. 69,454

Term of patent 14 years

To all whom it may concern:

Be it known that I, Reuben Robert Smith, a citizen of the United States, residing at Philadelphia, in the county of Philadelphia and State of Pennsylvania, have invented a new, original, and ornamental Design for a Bottle, of which the following is a specification, reference being had to the accompanying drawing forming part thereof.

I claim:

The ornamental design for a bottle as shown.

REUBEN ROBERT SMITH.
